Specification of Letters Patent. Patented Apr. 16, 1918.

Application filed August 7, 1917. Serial No. 184,864.

To all whom it may concern:

Be it known that we, THOMAS GARMONDS-WAY WRIGHTSON and JUSTUS MAGNUS RINGQUIST, subjects of the King of Great Britain, 5 residing at Teesdale Iron Works, Thornaby-on-Tees, England, have invented a new and useful Improvement in Hoists, of which the following is a specification.

This invention relates to improvements in 10 and connected with hoists especially adapted for charging blast furnaces. In such hoists a carriage which is raised and lowered in or upon a hoist frame supports a skip or bucket.

According to this invention the skip descends by its own weight to deliver its charge 15 and means independent of the hoisting rope are provided for lowering the skip.

The invention is illustrated by the accompanying drawings, Figure 1 of which is a 20 diagrammatic view of a blast furnace and hoist; Fig. 2 is a plan and Fig. 3 a side elevation of a carriage and skip in an arrangement when one toggle lever is employed, and Figs. 4 and 5 are similar views when two 25 toggle levers are employed.

1 is an inclined hoist frame the top of which is above the mouth 2 of a blast furnace 3. 4 is a carriage which supports a skip 5 and which has wheels 6 running on 30 rails 7 on the hoist; the carriage is raised and lowered upon the hoist frame 1 by means of a hoisting rope 8 which passes over pulleys 9, 10, to a winding drum 11, the weight of the carriage and skip being balanced by a counterweight 12. 13 is a rope by means of which the skip is lowered as 35 hereinafter described, and which is attached to the carriage 4 and passes around a pulley 14 to the winding drum 11.

40 Referring to Figs. 2 and 3, the carriage 4 consists of two crossheads 15, 16, of the width of the hoist frame 1, connected together by a toggle lever whose two members 17, 18, are pivoted together at 19 a friction roller 20 being mounted on the pivot. The hoisting rope 8 is connected to the lower crosshead 16, and another rope 21 for supporting the skip passes over a pulley 22 and is also attached to the crosshead 16. The 45 rope 13 is attached to the crosshead 16 and is led to the winding drum as before stated. On the hoist frame 1 is a guide 23 upon which the friction roller 20 runs causing the 50 toggle lever to hold the crossheads 15, 16,

apart. At the top of the hoist the guide 23 55 extends away from the hoist as shown at 24, thus leaving the pivot 19 unsupported and allowing the crosshead 16 to approach the crosshead 15 under the action of the weight of the skip 5. The lowering of the skip to 60 the mouth of the furnace is controlled by the rope 13.

In Figs. 4 and 5 the carriage as before consists of two crossheads 15, 16, which are held apart by two toggle levers, one consisting of 65 two members 25, 26, pivoted together at 27 and having a friction roller 28 upon the pivot, while the other consists of two members 29, 30, pivoted together at 31 and having a friction roller 32 upon the pivot. In 70 this case two guides 33 and 34 are provided, one at each side of the hoist.

In operating the hoist the skip 5 is attached to the carriage 4 at the bottom of the hoist as shown in full lines in the drawing; 75 the hoisting rope 8 is then wound on to the drum 11 causing the carriage 4 to ascend until it reaches the top of the hoist as shown in dotted lines. The skip 5 is then lowered on to the top of the furnace to deliver its 80 charge.

The method of operating the hoist and the details of construction of the carriage are the subject of a concurrent application Serial No. 184,865, filed August 7, 1917. 85

What we claim is:—

1. A hoist frame, rails upon the hoist frame, a carriage traveling upon the rails, a skip supported by the carriage, a rope for hoisting the carriage, a toggle lever pivoted to the carriage, means for controlling the movement of the toggle lever, and a rope connected to the toggle lever for lowering the skip. 90

2. A hoist frame, a carriage traveling upon the frame, a skip supported by the carriage, a rope for hoisting the carriage, a toggle lever pivoted to the carriage, means for controlling the movements of the toggle lever, and a rope connected to the toggle lever for lowering the skip. 95

3. A hoist frame, rails upon the hoist frame, a carriage traveling upon the rails, a skip supported by the carriage, a rope for hoisting the carriage, a crosshead on the carriage, a hoisting rope attached to the crosshead, another rope supporting the skip 105 and attached to the crosshead, a toggle lever

pivoted to the crosshead and the carriage, a guide on the hoist controlling the movement of the toggle lever and means controlled independently of the hoisting rope 5 for lowering the skip.

4. A hoist frame, rails upon the hoist frame, a carriage traveling upon the rails, a skip supported by the carriage, a rope for hoisting the carriage, two crossheads on the 10 carriage, the hoisting rope being attached to one crosshead, another rope supporting the skip and attached to the same crosshead, a toggle lever pivoted to the crossheads, a guide on the hoist controlling the movement 15 of the toggle lever and means controlled independently of the hoisting rope for lowering the skip.

5. A hoist frame, rails upon the hoist frame, a carriage traveling upon the rails, a skip supported by the carriage, a rope for hoisting the carriage, a crosshead on the carriage, a hoisting rope attached to the crosshead, another rope supporting the skip and attached to the crosshead, a toggle 25 lever pivoted to the crosshead and the carriage, means for controlling the movement of the toggle lever and means controlled independently of the hoisting rope for lowering the skip.

30 6. A hoist frame, rails upon the hoist frame, a carriage traveling upon the rails, a skip supported by the carriage, a rope for hoisting the carriage, two crossheads on the carriage, the hoisting rope being attached to one crosshead, another rope supporting the skip and attached to the same crosshead, a toggle lever pivoted to the crossheads, means for controlling the movement of the toggle lever and means controlled independently of the hoisting rope for lowering the skip.

35 7. A hoist frame, rails upon the hoist frame, a carriage traveling upon the rails, a skip supported by the carriage, a rope for hoisting the carriage, a crosshead on the carriage, a hoisting rope attached to the crosshead, another rope supporting the skip and attached to the crosshead, a toggle lever pivoted to the crosshead and the carriage, 40 a guide on the hoist controlling the movement of the toggle lever and a rope attached to the crosshead for lowering the skip.

50 8. A hoist frame, rails upon the hoist frame, a carriage traveling upon the rails, a

skip supported by the carriage, a rope for hoisting the carriage, a crosshead on the carriage, a hoisting rope attached to the crosshead, another rope supporting the skip and attached to the crosshead, a toggle lever pivoted to the crosshead and the carriage, means for controlling the movement of the toggle lever and a rope attached to the cross head for lowering the skip. 55 60

9. A hoist frame, rails upon the hoist frame, a carriage traveling upon the rails, a skip supported by the carriage, a rope for hoisting the carriage, a crosshead on the carriage, a hoisting rope attached to the crosshead, another rope supporting the skip and attached to the crosshead, toggle levers 70 pivoted to the crosshead and the carriage, guides on the hoist controlling the movement of the toggle levers and means controlled independently of the hoisting rope for lowering the skip. 75

10. A hoist frame, rails upon the hoist frame, a carriage traveling upon the rails, a skip supported by the carriage, a rope for hoisting the carriage, a crosshead on the carriage, a hoisting rope attached to the crosshead, another rope supporting the skip and attached to the crosshead, toggle levers 80 pivoted to the crosshead and the carriage, guides on the hoist controlling the movement of the toggle levers and a rope attached to 85 the crosshead for lowering the skip.

11. In a hoist for charging blast furnaces and the like, a hoist frame, a carriage traveling upon said frame, a skip carried by said carriage, a cable for connecting said skip with said carriage passing over a relatively stationary point of suspension on said carriage and having one end secured to said skip, supporting means mounted in said carriage and movable relatively thereto to 90 which the other end of said cable is connected, means on said hoist frame for effecting the movement of said relatively movable supporting means, a hoist rope connected to said relatively movable supporting 100 means, and a second rope connected to said relatively movable supporting means for controlling the lowering of the skip.

In testimony that we claim the foregoing as our invention, we have signed our names 105 this 11th day of July, 1917.

T. G. WRIGHTSON. [L.S.]
J. M. RINGQUIST. [L.S.]
